[57] CLAIM

The ornamental design for an embroidery hoop holder, as shown and described.

DESCRIPTION

FIG. 1 is a perspective view of an embroidery hoop holder showing my new design;

FIG. 2 is a front elevation thereof;

FIG. 3 is a right side elevation thereof;

FIG. 4 is a top plan view thereof;

FIG. 5 is a bottom plan view thereof;

FIG. 6 is a left side elevation thereof;

FIG. 7 is a rear elevation thereof;

FIG. 8 is a side elevation of a second embodiment of that shown in FIG. 1, the top portion only shown for ease of illustration; and

FIG. 9 is a front elevation thereof.

FIG. 1FIG. 2FIG. 4FIG. 3FIG. 9
